Primary Examiner — Steven J Czyz

(57) **CLAIM**

The ornamental design for an electric cooker, as shown and described.

DESCRIPTION

1. Electric cooker

1.1 Front

1.2 Back

1.3 Left

1.4 Right

1.5 Top

1.6 Bottom

1.7 Perspective

The broken line shown in the reproduction 1.6 depicts portions of the electric cooker that form no part of the claimed design.

1 Claim, 7 Drawing Sheets(56)
